DESIGN FOR A SUITCASE

Morris Gralnick, Philadelphia, Pa., assignor to Gralnick Bros., Incorporated, Philadelphia,
Pa.

Application January 16, 1940, Serial No. 89,498

Term of patent 7 years

To all whom it may concern:

Be it known that I, Morris Gralnick, a citizen of the United States, residing at 2407 Bryn Mawr Avenue, in the city and county of Philadelphia and State of Pennsylvania, have invented a new, original, and ornamental Design for Suitcases, of which the following is a specification, reference being had to the accompanying drawing, forming part thereof.

I claim:

The ornamental design for a suitcase, as shown.

MORRIS GRAZNICK.
